SHADE FOR WAND SUPPORTED, WALL OR SIMILAR LIGHTING FIXTURES

Anthony A. Dwyer, 3320 Wonderview Drive, Los Angeles, Calif.; Lloyd L. Garnell, 8029 Coldwater Canyon, North Hollywood, Calif.; Norman C. McClay, 1430 Elm Ave., Glendale, Calif.; and Ray Sealock, 2313-C Burbank Blvd., Burbank, Calif.

Filed Nov. 6, 1961, Ser. No. 67,396

Term of patent 14 years

(Cl. D48—16)

FIG. 1.

FIG. 2.

FIG. 3.

FIGURE 1 is a plan view of the shade for wand supported, wall or similar lighting fixtures.

FIGURE 2 is a side elevational view of the shade for wand supported, wall or similar lighting fixtures.

FIGURE 3 is a section taken along line 3—3 of FIGURE 1.

We claim:

The ornamental design for a shade for wand supported, wall or similar lighting fixtures, substantially as shown.
